2 SHEETS—SHEET 2.

UNITED STATES PATENT OFFICE.

OLIVER E. VANASDALE, OF ERIE, PENNSYLVANIA.

WINDOW-SCREEN.

1,141,996.

Specification of Letters Patent.

Patented June 8, 1915.

Application filed May 27, 1914. Serial No. 841,315.

To all whom it may concern:

Be it known that I, OLIVER E. VANASDALE, a citizen of the United States, residing at Erie, in the county of Erie and State of Pennsylvania, have invented certain new and useful Improvements in Window-Screens, of which the following is a specification.

This invention relates to improvements in window screens of the class of rolling window screens in which the screen is arranged to be automatically rolled upon a drum when not in use, and to extend over the open portion of the window and to automatically accommodate itself to the size of the opening as the window is raised and lowered, and has for one of its objects to improve the construction and increase the efficiency and utility of devices of this character.

Another object of the invention is to provide a simply constructed device which may be attached without material structural change to sashes of various sizes and materials and which may be applied either to the upper or lower sash.

Another object of the invention is to provide a device of this character which may be readily disconnected from the sash and disposed out of sight when not in use.

Another object of the invention is to provide a simply constructed device of this character which is readily accessible for removal or repairs of the parts without removal from the window.

Another object of the invention is to provide a device of this character which will not be visible when the window is closed.

With these and other objects in view the invention consists in certain novel features of construction as hereinafter shown and described and then specifically pointed out in the claims; and in the drawings illustrative of the preferred embodiment of the invention Figure 1 is a front elevation of a conventional window viewed from the inside with the improvement applied to the lower sash. Fig. 2 is an enlarged vertical section on the line 2—2 of Fig. 1 with the lower sash closed. Fig. 3 is a horizontal sectional view, the frame, lower sash and guides being in section on the line 3—3 of Fig. 1, and the housing for the winding mechanism in section on the line 4—4 of Fig. 1. Fig. 4 is a view similar to Fig. 2 showing the improved device applied to the

upper sash. Fig. 5 is a detached perspective view of one of the roller brackets. Fig. 6 is a detail on the same scale as Fig. 1 illustrating the arrangement and operation 60 of the locking cam. Fig. 7 is a sectional detail illustrating a modification in the construction.

Corresponding and like parts are referred to in the following description and 65 indicated in all the views of the drawings by the same reference characters.

The improved device may be applied without material structural change to windows of various sizes and various makes and be 70 applied to the upper or lower sash without material structural change, and for the purpose of illustration is shown applied to a conventional window-frame and its sash in which 10 represents a window-frame including the lintel or head, 11 the casing, 12 the stool or inside sill, 13 the upper sash, 14 the lower sash, and 15 the inside stops, these parts being of the usual construction.

The improved device will be located upon 80 the stool or inside sill 12 when applied to the lower sash and will be attached to the lower side of the lintel portion of the frame when applied to the upper sash.

The improved device includes a casing 85 for containing the rolling drum and other mechanism and comprises the base 16, ends 17, top 18 and front 19, the front of the casing being preferably hinged at 20 to the bottom 16 while the top 18 is preferably 90 hinged at 21 to the front 19 so that the interior of the casing is readily accessible for installing the screen rolling mechanism and for removing or repairing the same without destroying any of the parts. The casing 95 opens at its rear side toward the sash with its top 18 spaced at its rear edge from the inner face of the sash, as shown. Secured to the bottom member 16 of the casing at its ends are L-shaped brackets 22, one of the 100 brackets having a bayonet slot 23 while the other bracket is provided with a circular bearing 24. The brackets are designed to support the journals of a spring actuated winding roller comprising a shell or casing 105 25 which is provided with a circular bearing or journal 28 at one end to engage in the circular bearing 24 and with a core member 29 extending through the opposite end and having a flat terminal 30 to engage in the 110 bayonet slot 23. A spring 31 surrounds the core 29 and is connected at one end at 32

to the core and at the other end at 33 to the shell or roller 25. The spring is so arranged that when the shell 25 is rotated in one direction the spring will be wound up, 5 and then when the shell is released the reaction of the spring will wind the drum in the opposite direction. Each of the brackets 23 is likewise provided with an open slot 34 to receive the journals of a guide roller 10 35, the latter being spaced away from the spring winding roller 25. The screen material is represented conventionally at 36 and is attached at one end to the roller 25 and passes beneath the guide roller 35 and is secured at its opposite end in a strip 37, the latter being detachably connected by screws 15 or other suitable devices 38 to the inner face of the lower member of the lower sash 14 or to the upper member of the upper sash 13, as 20 the case may be.

Attached to the confronting faces of the inside stops 15 are guide strips 39 each having a vertical groove 40 to receive the projecting edge of the screen material 36. The 25 holding strip 37 extends only between the confronting faces of the guide strips 39 and is slidably disposed between them, while the screen material projects at its edges beyond the ends of the strip 37 and into the guide 30 grooves 40. By this means the joint between the screen material and the strips 39 is continuous and insect-proof as it runs up and down with the sash. Thus, no open 35 spaces occur between the edges of the screen material and the strip, no matter in what position the parts may be disposed.

The force of the spring 31 is continuous, or exerts a continuous winding force upon the screen material, consequently when the 40 sash is open the pulling force of the spring would have a tendency to close the sash, and to prevent this, it may be necessary to apply a holding device to the sash, and for the purpose of illustration a conventional cam device 41 is shown applied to one of the guide strips 39 in a position to engage the sash and lock the same in any desired position. By 45 this simple arrangement when the sash is in its lower or closed position the screen material will be automatically wound upon the drum or roller 25 and be entirely concealed within the casing, and no portion will extend over the glass of the sash. Consequently, when the sash is closed the screen 50 material does not obstruct the view. Then, when the sash is raised the screen material will be unwound from the drum and entirely 55

cover and protect the opening between the sash and the sill, when applied to the lower sash, or between the upper sash and the 60 lintel of the frame when applied to the upper sash.

The improved device is simple in construction, can be inexpensively manufactured and applied and without disfiguring 65 the sash or presenting an unsightly appearance.

Having thus described the invention, what is claimed as new is:

1. In a device of the class described, a casing adapted to be attached to a window and including a cover member spaced at its inner edge from the path of the adjacent sash member of the window, a holding strip adapted to be attached to said sash and to 70 completely fill the space between the casing cover and the sash when the sash is closed, the upper edge of the strip being flush with the outer face of the cover member and forming a continuation of the same, and 75 screen material attached at one edge to said strip and adapted to be disposed within said casing.

2. In a device of the class described, a casing adapted to be attached to a window, 80 brackets within said casing and having journal bearings and open slots, a spring actuated roller having journals engaging the bearings of said brackets, a guide roller having journals detachably engaging said open 85 slots, and screen material connected at one end to said roller and adapted to be connected at the other end to a window sash and engaging over said guide roller.

3. In a device of the class described, a casing 90 adapted to be attached to a window, brackets within said casing and having journal bearings and open slots, a spring actuated roller having journals engaging the bearings of said brackets, a guide roller having 95 journals detachably engaging said open slots, grooved guide strips adapted to be attached to a window, and screen material connected at one end to said roller and adapted to be connected at the other end to a window 100 sash and engaging by its edges in the grooves of said strips.

In testimony whereof I affix my signature in presence of two witnesses.

OLIVER E. VANASDALE. [L. 8.]
